and in Switzerland July 15, 1930

3 Claims. (Cl. 58—80)

This invention relates to a watch with a covered dial.

It is characterized by the feature that the watch is so constructed that the movements of the dial lid effect the winding of the watch.

The accompanying drawings show three examples of construction of a watch according to the invention, which is in the form of a wrist watch; of these

10 Figs. 1 and 2 are respectively front views of the closed and opened watch according to the first example;

Fig. 3 is a view thereof from below after the lid has been removed;

15 Figs. 4 and 5 are two longitudinal sections thereof, which show various parts in different positions;

20 Figs. 6 and 7 are front views of the watch according to the second example and in which the works have been taken out; and

Fig. 8 is a similar view of the third example.

The wrist watch according to Figs. 1 to 5 has a casing *a* consisting of the rectangular middle portion *b*, a bottom *c* fixed by means of an indent, 25 a bezel *d* formed with the middle part of the casing and a lid *e* which is fitted so that it can swing about *f* and which is kept in its closed position by means of a closing clasp *g*. Lugs *h* of the middle portion of the casing have pins *i* for the 30 purpose of supporting the band *j*.

The lid *e* has a toothed circular sector *k* which engages with a tooth *l* of a generally U shaped slide *m*. This slide *m* is arranged so as to be 35 slidable longitudinally in the middle portion *b* of the casing and is acted upon by two springs *n* which give it the tendency to go into the position corresponding to the closed lid. It also has a pusher *o*, which lies in an opening *p* of a side plate *q* of the middle portion of the casing, between the two lugs *h*. A complete plate *r* connects the other two lugs *h* and has the same appearance as the plate *q* and the pusher *o* so that the casing *a* has a symmetrical shape.

The toothed wheel *s*, which engages in the teeth 45 of the spring barrel, meshes with a toothed wheel *t* provided with a ratchet wheel *u*. The pawl *v* of this ratchet wheel is swingably secured at *w* on one arm of the slide *m* in such a manner that every pressure exerted on the pusher *o* for the 50 purpose of opening the lid results in a rotation of the ratchet wheel *u* by means of the pawl *v*. An L shaped spring *x* acts upon the pawl and rests on a guiding disc *y*, arranged so as to be rotatable about *z*. By rotating this guiding disc 55 *y*, the strength of the spring action can be ad-

justed. In order that the spring of the clockwork should not be wound beyond a given limit, the guiding disc *y* is adjusted so that the pawl *v* at the given instant jumps from tooth to tooth over the ratchet wheel *u* without further winding the clockwork spring.

60 The watch described is operated as follows:—

In Figs. 1, 3 and 4 the lid *e* is closed, the slide *m* and the pusher *o* are on the left (Fig. 4), the springs *n* are somewhat compressed and the 65 pawl *v* does not touch the ratchet wheel *u*.

If now one wishes to read the time, the pusher *o* is operated from left to right (Fig. 4). Its tooth *l* acts upon the toothed sector *k* and effects the opening of the lid by overcoming the 70 resistance of the closing clasp *g*. Owing to the said displacement of the pusher *o* and, consequently, of the slide *m*, the springs *n* are compressed and the pawl *v* rotates the ratchet wheel *u*—assuming that the tension limit of the 75 clockwork spring has not been reached—and the clockwork spring is thus wound up (Fig. 5).

On releasing the pusher *o*, the springs *n* return the slide *m* into its initial position, and the lid *e* is closed.

80 The adjustment of the time is effected by means of a crown fitted in the casing *a*.

The wrist watch according to Figs. 6 and 7 again consists of a casing *a*, a middle portion *b* of the casing, a bottom *c*, as well as a slide 85 *m* which is approximately U-shaped. The slide *m* is again moved in the middle portion *b* of the casing by acting on the pusher *o* against the action of the springs *n*.

The movements imparted to the slide *m* also 90 effect an uncovering of the dial in the manner already described.

The slide *m* is provided with a slot *1* which is arranged in its direction of movement and in which a member *2* carrying the pawl *v* can move. 95 The pawl *v* is in this case also intended to rotate the ratchet wheel located at *u*.

The to and fro movement of the slide *m* is transmitted to the member *2* through a spring 100 *3* which, on the one hand is fixed to the slide *m* at *4* and, on the other hand, presses with its free end at *5* against the said member. Consequently, assuming that a sufficiently strong resistance does not act against the spring *3*, the member *2* moves with the slide *m* in the same 105 manner as if it were fixed thereto.

If, however, during the winding of the watch 110 effected by the movements of the slide, the increasingly stressed spring of the clockwork opposes an increasing resistance to the winding, it

will finally happen that the pawl *v* can no longer operate the ratchet wheel *u*, since the spring 3 will then yield, and the movements of the slide will remain inoperative on the ratchet wheel *u*. Fig. 7 shows the forwardly pushed slide *m*, which, although it has therefore uncovered the dial, has not taken the member 2 with it, on account of the yielding of the spring 3.

Obviously the winding ceases earlier or later according to the tension of the spring 3. In order to be able to adjust this tension, an eccentric 6 is provided, which acts upon a lever arm of the spring 3 and renders the tension of this spring adjustable as desired. A screw permits this eccentric to be screwed tight in the chosen position.

Since the pawl *v* does not now have to escape the ratchet wheel, it is advisable to provide it with more than one tooth. Instead of the pawl a rack could be used.

The wrist watch according to Fig. 8 likewise consists of a casing *a*, a middle portion *b* of the casing, a bottom *c*, as well as a slide which is not represented but the direction of movement of which is indicated by an arrow *F* and to which a pin 7 belongs. The pin 7 is normally in the position represented by a full line and, when the watch is uncovered, is in the position 7' indicated by a dotted line. Springs, likewise not represented, return the slide and the pin 7 into their position of rest as soon as one no longer acts upon them.

At 8 the ratchet wheel is represented, which serves for winding the clockwork; the clockwork itself has not been represented.

At 10, at the bottom of the casing a lever is pivotally fitted on a screw 9. To the free end of this lever there is pivotally fitted the pawl 11, which is continually pressed to the ratchet wheel 8 by the action of the spring 12. The effect of the pressure is that the pawl continually engages in the wheel.

An elastic member i. e., a flat spring 13, which is secured by means of a screw 14 in a groove of a carrier 15, presses on the lever 10 to which there is therefore imparted the tendency to bear continually on the pin 7. In this way the movements performed by the pin 7 are imparted to the lever 10, which will then swing out of its position of rest, in opposition to the action of the spring 13. The position of the different parts which is given in broken lines corresponds to the position 7' of the pin 7.

The device works as follows:—

On uncovering the dial, the pin 7 is displaced with the result that the lever 10, the pawl 11 and the spring 13 are likewise displaced to 10', 11' and 13' respectively, and the pawl jumps back a few teeth on the locking wheel 8.

On releasing the slide, the pin 7 returns to its initial position, whilst the lever 10 is left under the influence of the spring 13. The spring 13 will return the lever 10 to its initial position up against the pin 7, so that the pawl, withdrawn from the position 11' to 11, will effect

a rotation of the ratchet wheel 8 in the winding direction.

The mode of operation just described of the spring 13 can naturally only take place if the force necessary for rotating the ratchet wheel 8 is smaller than the corresponding force due to the spring 13. Should these forces balance each other, or even the retaining action of the ratchet wheel preponderate, the various members would remain in the positions 10', 11' and 13' respectively until the winding can again be effected owing to the release of the clockwork spring. At this instant the various members will return to their initial positions 10, 11 and 13 respectively.

Obviously, the tension at which the clockwork is again wound, depends upon the force—i. e., the tension—of the spring 13. This tension can be adjusted by shifting the spring in the groove of the holder 15 and fixing it in the desired position by means of the screw 14.

What we claim and desire to secure by Letters Patent of the United States of America is:—

1. In a watch having clockwork and a dial and a lid therefor, a pivoted lever, a ratchet connected to the clockwork, a pawl engaged by the free end of said lever and in turn engaging said ratchet, a slide member for engaging said lever and moving same when the lid is opened, in a direction to ratchet idly over the ratchet wheel, a spring-safety member engaging against said lever, said slide also tensioning said spring-safety member when the lid is opened, the closing of the lid releasing said spring-safety device whereby an opposite and winding movement of the ratchet is effected.

2. In a watch having clockwork and a dial and a lid therefor, a pivoted lever, a ratchet connected to the clockwork, a pawl engaged by the free end of said lever and in turn engaging said ratchet, a slide member for engaging said lever and moving same when the lid is opened, in a direction to ratchet idly over the ratchet wheel, a spring-safety member engaging against the upper side of said lever, said member being adjustably mounted by one end in the case and its power being variable by varying its effective length.

3. In a watch having clockwork and a dial and a lid therefor, a pivoted lever, a spring at the lower side of the free outer end of the lever, a pawl pivoted to said free end, said spring bearing against said pawl so that said spring presses said pawl against the winding-ratchet wheel of the clockwork, an auxiliary spring co-operating with the middle of the upper side of said lever, a slide member co-operating with the lid, said slide pivoting the lever in a direction for ratcheting idly over said ratchet, and thereby tensioning said auxiliary spring, when the lid is opened, the slide, when closing the lid, releasing said auxiliary spring and returning said lever, whereby the pawl operates said ratchet in the winding direction.
